UNITED STATES PATENT OFFICE.

ADRIAN S. JONES, OF REDWOOD CITY, CALIFORNIA.

TANNING APPARATUS.

1,364,379.

Specification of Letters Patent.

Patented Jan. 4, 1921.

Application filed April 22, 1919. Serial No. 291,908.

To all whom it may concern:

Be it known that I, ADRIAN S. JONES, a citizen of the United States, residing at Redwood City, in the county of San Mateo and 5 State of California, have invented new and useful Improvements in Tanning Apparatus, of which the following is a specification.

The present invention relates to improvements in apparatus for tanning leather. The 10 object of the invention is to provide an apparatus so constructed that a suitable number of skins, suspended in a vat containing liquid, may be automatically moved through the liquid and during such movement may 15 be so folded as to open the pores of the skins to permit the tanning liquid to enter said pores in order to better preserve the skins, that is, so that the tanning action of the liquid on the skins may be as effective 20 as possible.

In the accompanying drawing, Figure 1 is a broken perspective view of my invention; Fig. 2 is a side view of a ball-bearing carriage.

Referring to the drawing, 1 indicates a tanning vat having two portions, a deep portion 2 and a shallow portion 3. On the upper edges of the side walls 4 of said vat, (one only being here shown), can travel 25 balls 6 mounted in recesses in the under sides of side members 7 of a carriage 8. Between, and extending above and below, said side members 7 are contained vertical members 9 which are supported from said 30 side members by tie-rods 11 extending around the bottoms of said side members. Slidable in vertical slideways 12 in said vertical members are plates 13, through holes 35 14 in which plates extend round bars 16, to 40 which are connected the upper ends of portions 17 of skins. Said plates are held in any desired position in said guideways by means of round bars 18 which extend through opposite holes 19 in the plates and 45 the projecting ends of which rest upon longitudinally extending members 21 of the carriage, between transversely extending members 22, said longitudinally and transversely extending members being both supported 50 by the side members 7. The transversely extending member 22 on the front side of said vertical members 9, and also a transversely extending member 23 on the rear side of said vertical members but at a higher elevation, are connected by oblique tie-rods 25 and to under sides of said transversely ex- tending members 22 are connected pairs of fingers 24, 26, of which the fingers 24 curve upwardly and the fingers 26 curve downwardly. Between the fingers of the several 55 pairs are sprocket chains 27, which travel around front and rear sprocket wheels 28, 29, on transverse shafts 31, 32, in suitable bearings 33, 34 extending upward from extensions 36, 37, from the side walls of the 60 tank. One of said shafts, as the shaft 31, carries also a pulley 38 by which it may be driven from any suitable source of power. Closely adjacent to the corner 41, dividing the shallow from the deep portion of the 65 tank, are rollers 42, 43, which facilitate the movement of the leather sheets around said corner.

As the sprocket chains 27 travel continuously, short bars 44 attached to said chains 70 engage alternately the fingers 24, 26. In traveling with said chains in their lower position, said bars engage the upwardly curved fingers 24 and move the carriage in one direction, when the chains travel around 75 said sprocket wheels, said bars 44 leave the fingers 24, and as the bars travel with the chains in their upper position, they engage the downwardly curved fingers 26 and thus move the carriage in the opposite direction. 80 Thus the carriage and the skins suspended therefrom are given a horizontal reciprocating movement. When the skins are hanging down in the deep portion of the tank, they hang directly downward, but when the 85 carriage is moving over the shallow portion of the tank, the skins hang partly in the shallow portion and partly in the deep portion of the tank, less and less of the skins entering the deep portion of the tank as the carriage moves toward the end of the shallow portion remote from the deep portion. When the carriage reaches said end of the 90 shallow portion, said skins extend for the greater part of their lengths upon the bottom of the shallow portion. When the carriage returns, the skins are bent or folded. This folding of the skins is very advan- 95 tageous as it enables the tanning agent in the vat to enter the pores of the skins and thus more effectually tan the leather. 100

I claim:—

1. A tanning vat, a carriage, means for reciprocating the carriage horizontally, means for suspending from said carriage 110 sheets of material, and an obstruction in the vat against which said sheets impinge and

fold upon as they reciprocate in a horizontal direction therein.

2. A tanning vat, a carriage, means for reciprocating said carriage horizontally, 5 means for vertically adjustably suspending from said carriage sheets of material, a shelf-like portion raised upon the bottom of said vat arranged to impinge against said sheets in their reciprocating movement and 10 to fold the same thereon.

3. A tanning vat, a carriage, means for reciprocating said carriage, means for suspending upon said carriage sheets of material, a shelf like obstruction in said vat 15 raised upon the bottom thereof against which said sheets impinge in their movement, said obstruction having a vertical and horizontal surface, and rollers pivotally supported upon said obstruction nearer the 20 juncture of said surfaces.

4. A tanning vat, deeper at one portion than at another, a carriage, and means, ver-

tically adjustable on said carriage, for suspending from said carriage sheets of material of greater length than the depth of the 25 shallower portion of said vat, means for reciprocating said carriage to cause the sheets of material to move horizontally from one portion of the vat to the other and into contact with the shallow portion. 30

5. A tanning vat, deeper at one portion than another, a carrier, means for suspending from said carrier sheets of material, means for reciprocating said carrier, comprising an endless chain, vertically disposed 35 sprocket wheels around which the chains travel, bars on said chain, and devices immediately below the lower portion and above the upper portion of said chain respectively against which said bars abut, 40 each device extending toward the adjacent portion of said chain.

ADRIAN S. JONES.
